NOAH WEBSTER RASNICK, OF NORA, VIRGINIA.

GATE LOCKING AND OPERATING MECHANISM.

1,279,000.

Specification of Letters Patent. Patented Sept. 17, 1918.

Application filed August 16, 1916, Serial No. 115,275. Renewed February 9, 1918. Serial No. 216,391.

To all whom it may concern:

Be it known that I, NOAH W. RASNICK, a citizen of the United States, residing at Nora, in the county of Dickenson and State 5 of Virginia, have invented a new and useful Gate Locking and Operating Mechanism, of which the following is a specification.

The present invention relates to an improvement in gate locking and operating 10 mechanism, adapted particularly for light gates to be opened and closed by persons, when entering and leaving an inclosure; for instance, a yard, a mine, behind a counter, an office rail, and the like.

15 It is an object of this invention to provide a gate of this character with an operating mechanism, which also locks the gate when closed, and which may be actuated by a foot pedal to release the lock, and to then 20 open the gate, the invention providing novel means for automatically closing the gate when the mechanism is released by the person after passing through the gate, the closing means being releasable to permit the 25 gate to remain open when desired.

Another feature of the invention is to provide a gate locking and operating mechanism of this character, which occupies but 30 relatively small space, which has the greater part of the mechanism located beneath the gate and out of the way, and which may be applied to gates without detracting from the general appearance and strength of the gate.

The above, and other objects and 35 advantages of this invention, will be more specifically brought out in the following description of the present preferred embodiments of the invention, the same being illustrated in the accompanying drawing, 40 wherein—

Figure 1 is a side elevation of a gate with its locking and operating mechanism constructed according to the present invention.

Fig. 2 is a longitudinal sectional view, 45 taken through the base of the gate, showing the parts in closed position in full lines, and showing the gate and the mechanism in open position in dotted lines.

Fig. 3 is a vertical transverse section, 50 taken through the gate on the line 3—3 of Fig. 1, showing one of the chambers within the base to receive the gate operating crank, distant parts being omitted.

Fig. 4 is a vertical transverse section, 55 taken through the gate on the line 4—4 of Fig. 1.

Fig. 5 is a fragmentary top plan view of the base, showing one of the crank connections, and the arrangement of the operating 60 pedals.

Fig. 6 is a fragmentary vertical sectional view, taken on the line 6—6 of Fig. 1, showing the combined operating and locking levers, and the pedals carried thereby.

Fig. 7 is a detail perspective view of the 65 lower end of one of the combined supporting and operating arms.

Fig. 8 is a detail perspective view of one 70 side of a modified form of supporting and operating arm.

Fig. 9 is a similar view, disclosing a modified form of the supporting arm used at the outer end of the gate.

Fig. 10 is a detail perspective view of the 75 inner end of one of the operating levers, showing the finger thereon, and showing a portion of the pedal carried by the finger.

Referring to this drawing, 10 and 11 designate a pair of vertical opposed gate sections, which may be of any approved form, 80 and which are shown in the present instance as comprising rows of vertically disposed slats, secured in position by upper and lower pairs of battens 12 and 13, respectively. Each gate section is hingedly or pivotally 85 connected to the upper ends of supporting arms 14 and 15, the arms 14 being connected to the inner adjacent ends of the gate sections 10 and 11, while the arms 15 are connected to the remote or outer ends of the 90 gate sections.

The arms 14 each comprise a pair of rods secured at their upper ends, by a pivot bolt 16, against the opposite sides of the adjacent gate section, as shown in Fig. 3. The rods 95 diverge downwardly from the pivot bolt 16 at the opposite sides of the adjacent gate section, and have their lower ends turned inwardly at an abrupt angle toward each other to provide horizontal transversely registering journals 17. These journals 17 are mounted in bearing blocks 18 held, by bolts 19, to the upper face of a base or foundation 20. The bolts 19, as shown in Fig. 3, have their lower headed ends embedded in the 105 preferably cementitious base 20.

The inner ends of the journals 17 of each arm 14, are bent at substantially right angles, and in parallelism with one another, outwardly away from the meeting ends of 110 the gate sections 10 and 11, and are connected at their outer ends by a pin or bear-

ing portion to provide an outwardly extending crank 21 on the lower end of each arm 14, and beneath the gate.

The outer arm 15 of each gate section is 5 of similar form, with the exception that, as shown in Fig. 4, the inner ends of the journals 17 terminate in spaced apart relation and have no crank portion.

The bearing blocks 18, which are prefer- 10 ably arranged in pairs, one pair for each journal 17, are spaced apart longitudinally on top of the base 20, a distance equal to the distance between the pivot bolts 16, which connect the upper ends of the arms 14 and 15 to the upper portions of the gate sections. Such pivoting of the arms 14 and 15 pro- 15 vides, with the gate sections, a parallel motion, by means of which the gate sections rise and fall in their movements toward and 20 away from each other. By this arrangement also, the weight of the gate sections 10 and 11 tend to hold them in their open and closed positions.

Preferably, each gate section is provided 25 with a coiled spring 22, having an arm 23 secured to the adjacent gate section, preferably below the upper batten 12. The opposite arm 24 of the spring is preferably curved downwardly and bent outwardly at 30 its free end to provide a lip 25 for detachable engagement against the lower end of the arm 15. This spring 22 is adapted to exert tension upon its adjacent gate section to raise the same and swing it into closed 35 position.

The base 20 is provided with a central longitudinal slot 26, which opens upwardly beneath the gate, and which is in the plane of the gate. The outer ends of the slot 26 40 are covered by plates 27 suitably secured to the base 20, and which extend a short distance inwardly toward the meeting ends of the gate sections. A pair of combined locking and operating levers 28 are placed in 45 the slot 26. The outer end of each lever 28 lies beneath the adjacent plate 27, to anchor the outer end of the lever in the slot 26. The levers extend inwardly toward each other beneath the gate, and, at intermediate 50 points in their lengths, have pivotal connection with the crank portions 21 of the inner supporting arms 14 of the gate sections. The levers 28 are recessed in their upper edges, and at their inner ends, to provide 55 locking shoulders 29 adapted, when the levers 28 are raised, as shown in Figs. 1 and 2, to engage against depending stops or projections 30 provided on the gate sections to retain said sections from opening. It will 60 be noted from the drawings, that the recesses and the shoulders 29 are of such depth that the gate sections cannot be spread apart to move the levers 28 down, and that the levers 28 must first be forced downwardly at 65 their inner ends to release the shoulders 29

from the stops 30 of the gate, prior to any appreciable movement of the crank portions 21.

Each lever 28 has upon its inner extremity an upwardly arched finger 31, which may be attached to one side of the lever 28, as shown in Fig. 10, and which extends upwardly into a recess 32 formed in the gate, by notches cut out of the lower inner corners of the sections 10 and 11. These fingers 31 are adapted to overlap, and each has its free end bearing against the upper edge of the extension 32^a of the opposite lever 28, so that both of the levers will be depressed upon the downward movement of either one 80 of the same.

The intermediate or highest portion of each finger 31 is preferably provided with a laterally extending pedal or projection 33, as shown to advantage in Figs. 6 and 10. 85 These pedals 33 are held at a suitable distance above the upper face of the base 20, by means of the upwardly arched fingers, to provide sufficient clearance beneath the pedals to admit of the depression of the 90 fingers and the consequent swinging of the operating levers 28.

The above structure is susceptible of various changes or modifications within the scope of the claims, and one modification is 95 shown in Figs. 8 and 9, of the drawing.

In Fig. 8, the combined supporting and crank arm 14^a is disclosed as in the form of a rod, which has its opposite ends secured to a vertical strip 34 adapted to lie flat against 100 the side of the gate section, the strip 34 swinging with the arm and as a part of the same. The lower end of the strip 34 is provided with an edgewise projection 21^a providing, with the opposed strip 34, a crank 105 portion for the arm 14^a.

In Fig. 9, a modification of the outer arm for supporting one of the gate sections is shown, and wherein the rod 15^a is similar to the rod 15, but is secured at its upper and lower ends to a strip 35, which reinforces the arm 15^a, and swings therewith, and as a part of the same. In Figs. 8 and 9 only one half of the arms 14^a and 15^a is shown, and it is understood that the other half is of 110 similar form, and is adapted for securement against the opposite side of the adjacent gate section.

In operation, when a person approaches the gate and desires to pass therethrough, 115 the foot is placed on the adjacent pedal 33, and the latter is forced downwardly toward the top of the base 20. Preferably, this base 20 is counter-sunk in the floor or earth, according to the location of the gate. The 120 downward movement of the pedal 33 forces the adjacent finger 31 therewith to depress the inner end of the adjacent lever 28. The free end of the finger engages the ledge or extension 32^a of the opposite operating lever 125 130

28, and both levers are thus simultaneously depressed. The outer ends of the levers 28 engage against the anchoring plates 27, and the downward movement of the levers, therefore, draws the cranks 21 downwardly into the chambers or enlargements 36 of the slot 26.

The downward movement of the cranks 21 turns the adjacent journals 17 and swings the arms 14 outwardly from each other to separate the gate sections 10 and 11. The initial downward movement of the inner ends of the operating levers 28, releases the locking shoulders 29 from the gate sections, as above described, so that the sections may be free to be raised and swung outwardly when the levers are further depressed.

The person holding the pedal 33 down passes through the gate, and then releases the foot from the pedal, so that the springs 22, which are contracted by the separation of the gate sections 10 and 11, are permitted to expand and automatically raise, and force together, the gate sections 10 and 11. The closing movement of the gate sections raises the operating levers 28 to normal position and brings the locking shoulders 29 against the stops 30 of the gate. Thus, the gate is automatically closed and locked when the pedal is released.

The opening and closing of the gate sections 10 and 11 may be limited by pins 37 rising from the base 20 in the path of studs 38 which project laterally from the gate sections, and which strike and rest against the pins 37. The pins 37 are so positioned that the pivot bolts 16 pass outwardly and inwardly over the lower pivotal mounting of the supporting arms 14 and 15.

40 The lips 25 of the springs 22 may be released from the adjacent arms 15, so that the gate sections 10 and 11 may rest in open position against the pins 37.

It is, of course, understood that various other means than the pedals 33 may be resorted to for the purpose of forcing the combined locking and operating levers 28 downwardly at their inner ends.

What is claimed is:

50 1. The combination with a vertically movable gate, of arms pivotally connected to the gate for supporting and moving the same, a pair of operating levers located beneath and in line with the gate and connected to said arms, and coacting means on said gate and said levers for locking the gate in closed position.

2. The combination with a gate, a pair of parallel arms pivoted at their upper ends to the gate and at their lower ends to a base, a crank portion on the lower end of one of said arms, an operating lever below said gate extending lengthwise thereof and swingingly supported at one end and connected intermediate of its ends to said crank portion for

turning the same and swinging said arms and said gate, and a pedal at the free end of the lever for actuating the same.

3. The combination with a gate, a pair of parallel arms pivoted at their upper ends to the gate and at their lower ends to a base, operating means located longitudinally of the gate and beneath the same and connected to said arms for moving the gate into open position, and coacting devices between the gate and said operating means to lock the gate when in closed position.

4. The combination with a base having a longitudinal recess therein, of a gate mounted above said base longitudinally of said recess, a pair of parallel arms pivoted at their upper ends to the gate and at their lower ends to the base, a crank portion on the lower end of one of said arms over said recess, an operating lever mounted in said recess and pivoted intermediate its ends to said crank portion, means acting as a fulcrum for one end of said lever, and means at the opposite end of said lever for actuating the same.

5. The combination with a base, of a pair of opposed gate sections mounted above said base, a pair of parallel arms pivoted at their upper ends to each gate section and at their lower ends to the base, a pair of levers mounted below said gate sections and connected to said arms, said levers overlapping at their adjacent ends, whereby movement imparted to one will simultaneously move the other to swing the gate sections, and pedals fixed to the overlapping ends of said levers and projecting in opposite directions to either side of the gate.

6. The combination with a pair of opposed gate sections, a pair of parallel arms pivotally supporting each gate section, a spring carried by each gate section and engaging an adjacent arm to yieldingly hold the gate sections in closed position, an operating means connected to one arm of each pair, and a connection between said operating means for simultaneously actuating the same to swing said arms and open the gate sections, the said springs being adapted to close the gate sections upon the release of the operating means.

7. The combination with a pair of opposed gate sections, a pair of parallel arms pivotally connected to each gate section for supporting the same, a crank portion on one arm of each pair beneath the gate, a pair of opposed operating levers pivoted upon said crank portions and extending longitudinally beneath the gate sections, overlapping fingers carried upon the inner ends of said levers and adapted to bear at their free ends upon the opposite levers, and pedals extending laterally from the fingers for engagement by the foot, whereby to depress said operating levers and move the gate sections into open position.

8. The combination with a pair of opposed gate sections, a pair of supporting arms pivoted to each gate section, a crank carried upon one arm of each pair, opposed operating levers arranged longitudinally beneath the gate sections and having pivotal connection intermediate its length with said cranks, means connecting the inner adjacent ends of said operating levers to cause them to move simultaneously, operating means connected to the levers for depressing the inner ends of the same and cause the gate sections to move into open position, and springs arranged between the arms and the gate sections for moving the latter into closed position upon the release of said operating means.
9. The combination with a pair of opposed gate sections, a pair of parallel arms hingedly connected to each gate section for supporting the same, springs connected to one arm of each pair for normally urging the gate sections into closed position, cranks on the opposite arm of each pair, an operating lever pivoted intermediate its length to each crank, connecting means at the inner adjacent ends of the operating levers to cause the simultaneous movement of the same, and operating means connected to the levers for depressing the same to actuate the cranks and the arms and open said gate sections.
10. The combination with a pair of opposed gate sections, and arms pivotally connected to each section for supporting the same, operating means connected to said arms and having a locking member thereon adapted for engagement with the adjacent gate section when the gate is closed to retain the sections in closed position, and means connected to said operating means to actuate the latter to first release the gate sections, and then turn said arms to swing the same and the gate sections into open position.
11. The combination with a pair of opposed gate sections, and a pair of parallel arms pivoted to each gate section to support the same, an operating lever for said arms extending longitudinally beneath the gate sections, a stop on each gate section, a locking shoulder on each operating lever for contact with the adjacent stop when the said gate sections are closed, and means connected to said operating levers for disengaging the shoulders from said stops prior to opening the gate.
12. The combination with a pair of opposed gate sections, and a pair of parallel arms pivoted to each section for supporting the same, a lever arranged longitudinally beneath each gate section, cranks on said arms having pivotal connection with the lever, means for anchoring said levers beneath the gate, overlapping fingers on the inner ends of said levers, pedals projecting laterally from said fingers to be engaged by the foot to depress the inner ends of said levers and open the gate sections, said levers having extensions at their inner ends for contact with the free ends of the opposite fingers whereby the levers may be simultaneously actuated, stops depending from the inner ends of the gate sections, and locking shoulders on said levers for contact with said stops when the levers are raised to lock the gate sections from movement.
13. The combination with a pair of vertically movable gates, of supports for swinging the gates to open and closed positions, and coacting pedal controlled means alining with and directly beneath the gates for action upon the supports to simultaneously move said gates to open position.
14. The combination with a pair of vertically movable gates, of supports for swinging the gates to open and closed positions, coacting pedal controlled means alining with and directly beneath the gates for action upon the supports to simultaneously move said gates to open position, and springs active upon said supports for the automatic closing of the same.
15. The combination with a pair of vertically movable gates, of supports for swinging the gates to open and closed positions, coacting pedal controlled means alining with and directly beneath the gates for action upon the supports to simultaneously move said gates to open position, springs active upon said supports for the automatic closing of the same, and foot pedals extending laterally at the division line of the gates from the point of coaction of said means for manually operating the same.

In testimony, that I claim the foregoing as my own, I have hereto affixed my signature in the presence of two witnesses.
